DISPLAY RACK

Walter H. Schray, Battle Creek, Mich., assignor to
United Steel and Wire Co.

Application June 5, 1953, Serial No. 25,341

Term of patent 3½ years

(Cl. D80—10)

fig. 1

Des. 177,644

PAGE 2

Figure 1 is a substantially front perspective view of a display rack, showing my new design.

Figure 2 is a front elevation view of said rack.

Figure 3 is a top view of said rack.

Figure 4 is a side elevation view of said rack.

Figure 5 is a rear elevation view of said rack.

I claim:

The ornamental design for a display rack, substantially as shown and described.
